Primary Examiner — Mojtaba Tehrani(74) *Attorney, Agent, or Firm* — Eversheds Sutherland (US) LLP(57) **CLAIM**

The ornamental design for a multi-accessory mount as shown and described.

DESCRIPTION

FIG. 1 is a top perspective view of a multi-accessory mount according to the disclosure;

FIG. 2 is a bottom perspective view thereof;

FIG. 3 is a right side view thereof;

FIG. 4 is a rear view thereof;

FIG. 5 is a front view thereof;

FIG. 6 is a left view thereof;

FIG. 7 is a top view thereof; and,

FIG. 8 is a bottom view thereof.

The broken lines in the drawings disclose unclaimed portions of the multi-accessory mount only and form no part of the claimed design.
